S. T. PEAT, OF FLORENCE, NEW JERSEY.

Letters Patent No. 92,541, dated July 13, 1869.

IMPROVEMENT IN AUGER-HANDLES.

The Schedule referred to in these Letters Patent and making part of the same.

To all whom it may concern:

Be it known that I, S. T. PEAT, of Florence, in the county of Burlington, and State of New Jersey, have invented a new and useful Improvement in Auger-Handles; and I do hereby declare that the following is a full, clear, and exact description thereof, which will enable others skilled in the art to make and use the same, reference being had to the accompanying drawings, forming part of this specification.

This invention relates to improvements in auger-handles, such as are used for holding shanks of various sizes and form, and adapted for readily attaching and detaching the same; and consists in certain improvements, designed to cheapen the construction and provide a more reliable holding-device.

Figure 1 represents a sectional elevation, and

Figure 2, a horizontal section of the same.

Similar letters of reference indicate corresponding parts.

A represents a metallic holder, which I prefer to form by casting.

It is provided with the horizontal hole *a*, for the wood handle, and the vertical socket *b*, for the reception of the shanks of the augers to be held, and a sliding clamping-jaw, *c*, for clamping against one side of the shank.

The said holder is provided with vertical grooves *d* in the sides of the vertical opening *b*, and lateral grooves *e* communicating therewith, and the clamp-

ing-jaw is provided with trunnions *f*, to slide in the said grooves and maintain the jaw in its position in the holder, while allowing it to slide to and from the shanks to be clamped.

The said jaw is provided with a right-angular notch, or groove in its face, for taking in the corner of a square shank, or clamping against the side of a round one, and a set-screw, *g*, is provided for moving and clamping the jaw to hold the augers.

Set-screws *h* are arranged in the side of the part A, opposite to the jaw C, at such an angle that when a square shank is to be held, they will bear fair upon the two sides of the same. They will also bear upon a round shank in this form, equally as well as in any other.

Having thus described my invention,
I claim as new, and desire to secure by Letters Patent—

The metallic holder A, cast in one piece, with the horizontal hole *a*, for the passage of the auger-handle, the vertical passage *b*, for the reception of the auger-shank, and with the interior angular grooves *d* *e*, adapted to receive the trunnions *f* of the adjustable jaw C, all constructed, arranged, and operating as described for the purpose specified.

S. T. PEAT.
